UNITED STATES PATENT OFFICE

2,037,402

BLOWER

John Leonard Taylor, Milwaukee, Wis.

Application December 7, 1931, Serial No. 579,448

8 Claims. (Cl. 230—141)

This invention relates to means for supplying Diesel or other engines with air under pressure for use in the charges furnished the cylinders in this class of prime movers, and an object of the invention is to generally improve the construction and operation of devices of this class.

A further object is to provide air supply means for an internal combustion engine which may be reversed with the engine, and further objects are 10 to provide the following:

Such a means in the form of a positive type of rotary blower;

Such a means which may be built in combination with the engine which it supplies as a unitary 15 structure;

The combination of a reversible engine and a positive type of rotary blower driven therefrom and connected to supply the engine with air, and so arranged as to supply the engine properly regardless of the direction of operation of the 20 engine and blower;

Such a structure which will be light, compact, and adaptable to form an inherent part of an engine;

25 A casing for such a blower having bracing means for obtaining the necessary rigidity which is arranged to furnish fluid passages;

Resilient connections between the engine and the rotary portions of the blower;

30 Air filtering means particularly adapted for incorporation in such a blower structure;

Gearing especially adapted for interposition between an engine and blower to give a desired rate change while conforming to the general 35 arrangement and contour of the structure;

Various details of structure and arrangement of parts for accomplishing the above objects, and other objects and advantages which will become apparent from the following specification and 40 accompanying drawing in which:

Fig. 1 is an end elevation of the improvement, partially broken away to disclose interior aspects.

Fig. 2 is a section on line 2—2 of Fig. 1.

Fig. 3 is a detail fragment of a valve indicated 45 in Figs. 1 and 2.

Fig. 4 is a fragmentary detail of the air filtering means.

Fig. 5 is a fragmentary view taken on the line 50 5—5 of Fig. 2.

Fig. 6 is a perspective view of a shaft element.

Similar reference characters apply to the same parts throughout the drawing and specification.

Referring to the drawing, H is a shell-like housing providing a chamber A wherein rotate inter-

passage H¹ whose inlet is guarded against unclean atmospheric conditions by a novel filtering arrangement or screen S. The indrawn air is then forced, under impeller pressure, through a passage H². Both passages, H¹ and H², are arranged about the chamber A. The passage H² is contiguous with an auxiliary passage or chamber M, offset from the housing H, and disposed about a preferably integral gear housing portion H³, the two passages forming a receiver of substantial volume for absorbing slight variations in output of the blower, or the demand of the engine, and preventing excessive variations in pressure.

The housing portion H³ is bolted or otherwise suitably fixed to the shell H, forming a companion closure wall with a cover plate C, which completes the aforesaid chamber A. The gear housing is flanged and fixed to the engine E. The chamber M is provided with an outlet M' at the point where it is fixed to the engine, where it abuts and registers with a charging air inlet passage or air manifold M² of the aforesaid engine, indicated by dotted lines in Fig. 2.

Intermediate the passages H¹ and H² are spaces or fluid ports A' open to the chamber A, the spaces being approximately radially disposed to the axis of the upper impeller, a desirable inclination of said spaces being thus obtained. One of these spaces operates as an intake, and the other as a discharge port, the direction of rotation of the impellers determining the character of the ports.

Each of said spaces is provided with an inlet and outlet valve, respectively V and V'. The aforesaid inclination of the spaces A' will offer the air current an easy flow through the inlet valve V at one space A', and the outlet valve V' at the opposite space A'. The path of air through valve V' is at a substantial angle to the valve element or flap, so that the stream impinges upon the flap and tends to keep it well removed from the seat as shown at the left of Fig. 1, while valve V, being of substantially larger capacity than valve V', does not need to open so widely to accommodate the flow. The flap of this valve therefore normally does not rise beyond the position shown at the right of Fig. 1, and the incoming stream of air or other fluid is directed toward the rotating impellers, and away from the flap V' above, so that there is no tendency for the incoming stream to tend to open the valve V' of the port which is for the moment the intake or suction port.

The present description applies to rotation of

the impellers P according to the plain arrows. A like explanation will be understood to apply when a reverse rotation obtains, in which case the valves open as shown by the dotted arrows.

5 The combined structure of the housing H and H³ is comparatively light, and in view of the fact that it overhangs, a certain rigidity must reside in the structure so that the chamber A will resist any distortion that would cramp the impellers, which approach each other and the chamber wall within close limits. Strength is added by dividing the passages H¹ and H² with the respective ribs h and h', preferably integral parts of the housing shell H. The rib walls 10 h are perforated to provide the openings h', the ribs h' having free edges at the screen S, which serve to support the screen against distortion by the external air pressure, leaving the passages H¹ and H² practically unobstructed, the 15 passages forming chambers open respectively to the outer air, and to the chamber M.

10 The drive for the impellers begins with the crankshaft E' to which shaft is fixed a flywheel 1, provided with blocks 1', the wheel being coupled to a driven member 2 by means of flexible 15 blades 2' intermediate the annularly disposed blocks 1' and the driven member, this coupling structure forming the subject matter of my co-pending application, filed September 26, 1931, 20 Serial No. 565,281.

15 The said member 2 is rigidly attached to a gear 3 by suitable bolts or the like 2''. The gear rotates about an enlarged shaft end 4 which is axially aligned with the crankshaft E', but separated therefrom. The gear 3, being connected to the fly-wheel 1 by means of driven member 2 and flexible blades 2', rotates with said wheel freely about said enlarged shaft end, being supported therefrom by anti-friction bearing 5. The 20 gear 3 meshes with a pinion 6, keyed or otherwise fixed to the shaft extension 7 of the upper impeller shaft 8, the diameter thereof being reduced at 8' to accommodate an adjusting nut k which functions to precisely fix the width between the cover plate C and the wall C' to give 25 suitable clearance for the impellers P.

25 The bearings x-x support shaft 8 and are received in depressions B-B', depressions B being sealed by closure disks w to form oil-tight 30 pockets. The two impellers P are mounted on similar shaft arbors, the lower shaft being designated by 8^a. Both shafts 8 and 8^a have fixed 35 thereon the respective and similar intermeshed synchronizing gears 9 and 10. The impeller shaft journals are kept lubricated by appropriate means from a convenient oil supply in the 40 crankcase of the engine, the lubricant being forced through tubes t and t' to both pockets B and B^a from which latter pocket it drains back to the crankcase through the tube t''.

45 The pressure generated by the impellers within the casing tends to bulge out the cover C and the wall C', this effect being guarded against by ribs c and c', preferably joined to the walls of 50 pockets B and B^a, for resisting any changing tendency in the flat walls of the chamber A.

55 Fig. 3 shows the detail constructions of the valves here employed. The edges at the spaces A' receive the grids G which carry suitably light flap-valves V-V' which are preferably, although not necessarily spring urged toward closed position. Fig. 4 is a detail of the air-filtering closure screen S wherein is arranged a loosely woven 60 felt or other filtering element F, protected

against being torn or from being forced out of position by air pressure by means of layers of wire netting N, which in turn, are clamped against the housing H by the frame of the screen S.

5 The operation of the mechanism should be clear from the above description, the engine driving, through flywheel 1 and driven coupling element 2, gear 3, which drives gear 6, thereby 10 operating upper impeller P, gear 9 on the impeller shaft driving the lower impeller through shaft 8^a, rotation of the impellers forcing air from one to the other of spaces or ports A', according to the direction of such rotation. If the 15 rotation of the upper impeller is clockwise, the 15 direction of movement will be from left to right as seen in Fig. 1, air being drawn through filtering material F into passage H¹, through valve V shown at the left in Fig. 1, and discharged through valve V' shown at the right, valve V at 20 the right remaining closed, and valve V' at the left remaining closed. The discharged air passes into chamber H², and into charging air inlet passage M'. Reverse rotation of the impellers, 25 as will be readily apparent from the figures, will cause movement of the air from right to left, valve V at the right remaining open, while valve V' at the left remains open, the remaining valves remaining closed, and the air as before flowing in through filtering material F, and out through 30 passage H² and inlet passage M'.

30 The apparatus therefore may be used without regard to the direction of operation of the engine into which it is built, and if the engine is reversible, as is customary in Diesel engine practice, for example, no difficulty is experienced with the charging air supply. Through the disclosed arrangement, a positive displacement type of rotary blower may be incorporated in an engine structure, and the advantages of the positive type 35 of blower enjoyed with a reversible engine. I understand that positive displacement types of blower have been used for charging internal combustion engines in the past, but insofar as I am aware, no attempt has been made to use such a 40 45 blower with a reversible engine, and no such blower has been developed which could be used with such an engine.

45 Any shocks which otherwise would develop from the inertia inherent in the rotors P upon sudden 50 changes in speed or other operating characteristics of the engine are absorbed in the flexible coupling 1-2 etc., and the whole structure has been so arranged that the coupling, the drive gears, and the synchronizing gears for the 55 impellers are compactly incorporated in the extension of the engine structure, the whole forming a compact, unitary, and efficient structure, both in economy of weight, and space occupied.

55 Having described the invention what I claim 60 and desire to protect by United States Letters Patent is:—

1. A blower air-compressor having; an engine crankshaft; intermeshed impellers; impeller gears 65 rotatively rigid with their respective impellers; one of said impeller gears rotatable with a driven pinion; the other impeller gear axially aligned with a driving gear actuating said pinion, said driving gear rotating freely about the axis of said other impeller gear, and at a different speed therefrom; a resilient coupling unitary with said driving gear; said coupling interlockable with a flywheel element keyed to the aforesaid crankshaft. 70

2. A blower air-compressor having, an impeller chamber within surrounding passages of greater 75

and lesser capacities, intermeshing impellers rotatable in said chamber, intermediate spaces dividing said passages, spring-urged flap valve closures controlling passage entrance to and from said spaces, the upper valve openings inclined to lie diagonally across the path of air currents passing therethrough for aiding ready opening of said flap valves, and enlarged lower valve outlet means whereby permitting a partially restricted flap opening in the greater passage to admit an air volume that is equal to the unrestricted outlet in the valve of the lesser passage.

3. A blower air-compressor having; an impeller chamber; intermeshing air-impellers rotatable in said chamber, an air-inlet serving said chamber; an air-filtering screen of restrained fibrous product restricting said air-inlet; oppositely arranged closure pairs comprising an inlet valve and an outlet valve; an air-outlet passage divided by perforate partitions; an auxiliary passage, arcuately parallel and adjacent said outlet passage, provided with a terminal opening registering with the mouth of an engine air-manifold, disposed between said chamber and said engine.

25 4. In a combustion engine the combination of an engine structure including a charging air inlet passage, a crankshaft, and a crank case structure rotatively supporting said crankshaft, a blower disposed to supply air to said charging air inlet, said blower including a housing and air displacing means supported in said housing for rotation in either direction, means for driving said displacing means from said crankshaft, an air inlet for said housing and said housing providing air spaces either of which may become a suction or a delivery port in accordance with the direction of rotation of said displacing means, said spaces being positioned to cooperate with said displacing means, a plurality of air passages leading between said air inlet, said ports, and said charging air inlet passage, and a plurality of valves operable by air displaced by said displacing means, controlling said passages, and operative to direct flow of air from whichever space is a discharge port to said charging air inlet passage in accordance with the direction of operation of said crankshaft.

5. In a combustion engine the combination of an engine structure including a crank case, a crankshaft rotatively supported in said crank case, a charging air inlet, and a blower connected to supply air to said charging air inlet, said blower comprising a blower housing providing an impeller chamber, an air displacing means supported in said chamber for rotation in either direction, connections for driving said displacing means from said crankshaft, an air inlet in said housing, said housing providing a plurality of air passages connected between said air inlet, said chamber and said charging air inlet, valve means disposed to control the flow of air in said passages, said valves being operative by movement

of air by said displacing means to direct the flow of air from said air inlet to said chamber and from said chamber to said charging air inlet regardless of the direction of operation of the crankshaft and said air displacing means.

5 6. The combination of an engine having a crankshaft and a charging air inlet passage, a blower casing carried by said engine, intermeshed air impellers in said casing, shafts journaled in said casing and carrying said impellers, impeller 10 gears rotatively rigid with said impellers and interconnected for maintaining correct rotative relation between said impellers, a driven pinion gear rotatively rigid with one of said impellers, a driving gear engaged with said pinion, journaled 15 on the shaft of the other impeller and driven from said crankshaft, and connections from said casing for conducting air from said impellers to said charging air inlet.

7. The combination of an engine having a 20 crankshaft and a charging air inlet passage, a blower casing carried by said engine and including an impeller chamber, means defining intake and discharge passages about said chamber, a plurality of intermeshed impellers supported in 25 said chamber for rotation in either direction, connections operative to drive said impellers from said crankshaft, said means providing spaces, each communicating with said chamber to form respectively an inlet or a discharge port according to the direction of rotation of said impellers, air actuated valve closures controlling the passage of air between said spaces and said passages, said valves being arranged to permit passage of air from said intake passage into either 30 space, and from either space into said discharge passage, but not the reverse, and connections providing for flow of air from said discharge passage into said charging air inlet.

8. The combination of an engine having a 40 crankshaft and a charging air inlet passage, a blower casing carried by said engine and including an impeller chamber, a plurality of intermeshed impellers in said casing, shafts journaled in said casing and carrying said impellers, synchronizing gears rotatively rigid with said impellers and interconnected for maintaining correct rotative relation between said impellers, a flexible coupling including a driving element mounted on said crankshaft, and a driven element 45 mounted on the shaft of the other impeller, and maintained thereby in correct relation with said driving element of said flexible coupling, means flexibly connecting said driving and driven elements, and connections from said casing for conducting air 50 from said impellers to said charging air inlet. 60

JOHN LEONARD TAYLOR.
